(57) **CLAIM**

The ornamental design of a supply pod dispenser, as shown and described.

DESCRIPTION

FIG. 1 is a front perspective view of the supply pod dispenser showing our new design;

FIG. 2 is a front view of the supply pod dispenser;

FIG. 3 is a back view of the supply pod dispenser;

FIG. 4 is a right side view of the supply pod dispenser;

FIG. 5 is a left side view of the supply pod dispenser;

FIG. 6 is a top view of the supply pod dispenser; and,

FIG. 7 is a bottom view of the supply pod dispenser.

The broken lines are provided for illustrative purposes only, and form no part of the claimed design. In addition, the portions of the dispenser that are not shown in the drawing do not form any part of the claimed design.

1 Claim, 7 Drawing Sheets
